CLAIM

The ornamental design for an electronic vaporizer device, as shown and described.

DESCRIPTION

FIG. 1 is a perspective view of the electronic vaporizer device according to our new design;

FIG. 2 is a first side elevation view thereof;

FIG. 3 is a second side elevation view thereof;

FIG. 4 is a third side elevation view thereof;

FIG. 5 is a fourth side elevation view thereof;

FIG. 6 is a top plan view thereof; and,

FIG. 7 is a bottom plan view thereof.

The broken lines in FIGS. 1-7 show portions of an electronic vaporizer device which form no part of the claimed design.
